ARTHUR W. MOREE, OF NEW YORK, N. Y.

WIND DEFLECTOR AND VENTILATOR

Application filed April 14, 1930. Serial No. 444,303.

This invention relates to an improved ventilator and wind deflector, the object being to provide a simple, strong and efficient device which can be quickly applied and removed and when in use in a window to direct the air from either of two directions into and through the window.

Another object of the invention is to provide a ventilator and wind deflector for windows which will direct air into a room adjacent the window, the structure being such that the parts may be quickly placed in operable position and quickly demounted.

A further object, more specifically, is to provide a ventilator and wind deflector to be used in windows wherein a comparatively simple and inexpensive frame is presented, and formed in such a way that the window sash will act as the principal means for holding the device in place, the frame held in place by the window sash acting as a support for the deflecting member.

In the accompanying drawings—

Figure 1 is a vertical sectional view through a window and associated parts with one embodiment of the invention shown applied thereto, certain parts of the device being shown in section;

Figure 2 is a front elevation of the structure shown in Figure 1;

Figure 3 is an enlarged detailed, fragmentary perspective view of one of the outward corners of the deflector shown in Figure 1.

In many dwellings, and particularly in apartment houses, it is difficult to cause the cooling breezes which may pass the house to enter into the windows of any room. This is particularly true where the room has only one window and has no opposite outlet through which the air may pass to secure a cooling breeze from the outside of the building.

In the present invention means have been provided which may be placed in an outside window and act to direct a breeze into the room. When a breeze is flowing from either of two directions the device is placed preferably in the lower part of the window and the upper part of the window is slightly

opened so that air passing the window will strike the device and be deflected into the room, and some of the air in the room will escape out through the open upper part of the window.

Referring to the accompanying drawings by numerals, 1 indicates a window frame of any desired kind, and 2 the lower sash. Arranged within the window frame 1 is a deflector frame 3 which carries the deflector member 4 which is preferably of canvas or other desired fabric. The frame 3 may be made of wood, metal or other desired material and is made comparatively light and provided at the upper end with socket members 5 and 6 which straddle the lower part of the sash 2 as shown in Figure 1 when the device is in use. Spurs 7 of any desired kind extend from the lower part of the frame 2 and are preferably forced a short distance into the window sill 8. In this way the frame 3 is anchored at the top and bottom.

Where the device is made of wood blocks 9 and 10 are secured to the frame by screws or other means, and these blocks carry the respective tubular sockets 11 and 12. If desired, other forms of holding means can be provided for the sockets 11 and 12, and particularly where the frame 3 is made of metal.

From Figure 1 it will be noted that socket 12 extends substantially horizontally, whereas socket 11 extends at an upward angle. By reason of this structure a single pin 13 may be used, said pin holding the rod 14 in place, while the angle of the socket 11 acts to hold the upper rod 15 in place. A connecting or spacing rod 16 connects the outer ends of rods 14 and 15 while the respective rods are held in place by lines of stitching 18, 19 and 20. In this way there is provided a hem on three edges and into these hems the various rods are fitted. Preferably the parts are so fitted that the canvas 4 is comparatively taut adjacent the rod 16 and extra full between the sockets 11 and 12.

By reason of this fullness 21, as shown in Figure 1, whenever a wind passes along the outside of the window at right angles to the window opening it strikes the canvas 4 and the part 21 will be forced to one side and

- thereby present an inclined surface which will deflect the air through the window and into the room. This action will take place when air flows in either of two directions.
- 5 If the canvas 4 was rigid, as would be the case with a piece of sheet metal, the air would be stopped and very little deflected through the window opening. As the edge 22 moves appreciably to one side centrally of the canvas 4, a decided half-funnel or inclined surface is provided and consequently the air may be readily deflected into the room.
- Whenever desired to remove the device, sash 2 is raised until it is disconnected from the sockets 5 and 6, and then the device may be moved up for a short distance and brought into the room. The rods 14 and 15 have a sliding fit with the sockets 11 and 12 so that these rods may be readily removed when it is desired to store the device.
- 20 From Figure 1 it will be noted that the device may be readily used without interfering with the usual inside screen and, consequently, the device may be used at any time, day or night, to secure a supply of fresh cool air.
- What I claim is:
1. A combined wind deflector and ventilator comprising a frame adapted to be placed in a window, a flexible sheet, an upper and lower rod carried by said frame and connected with said sheet, a spacing rod at the upper edge of said sheet for holding the sheet substantially taut at the outer edge, said sheet being full at the inner edge so that when air strikes the same the full edge will be deflected to one side so that the flexible member will present a deflecting surface for directing air inwardly through said window.
- 30 2. A device of the character described comprising a frame adapted to be placed in a window, means carried by the frame presenting a framework, and a fabric sheet connecting said framework, said fabric sheet being substantially taut at its outer edge and very full at its inner edge, so that the inner edge will be deflected to one side when air strikes substantially flatwise against the fabric, thus causing the air to be directed through said window.
- 40 3. A combined deflector and ventilator comprising a frame adapted to be placed in a window frame, means forming sockets at the top of said frame for receiving the lower part of the lower window sash carried by said window frame, a pair of bars extending from said frame, a fabric sheet secured at its respective edges to said bars, means at the outer edges of said fabric sheet for holding the same substantially taut, said fabric sheet at the inner end being full so that when air strikes either surface the air will be deflected to one side and thereby cause the fabric to present an inclined surface and direct the air through said window.
4. A combined deflector and ventilator comprising a frame adapted to be held in a window frame, a bar connected with the lower part of said frame and extending outwardly therefrom, a second bar connected with the upper part of said frame and extending outwardly therefrom, a fabric member connected to said bars, said fabric member being fullest at its inner edge so that when air strikes the fabric member from either side it will be deflected through said window.
5. A combined wind deflector and ventilator including a framework, means for extending the framework outwardly from a window frame, and a canvas covering said framework, said canvas at the outer edge being substantially taut and at the inner edge comparatively loose, so that air striking either surface will deflect the inner edge and thereby cause the air to be directed through said window opening.
6. A wind deflector and ventilator comprising a deflector frame adapted to be inserted into a window frame, a socket at the bottom of said deflector frame, a second socket secured to said deflector frame adjacent the top of the deflector frame, rods removably mounted in each socket, a fabric sheet connecting said rods and means for holding said fabric at the outer edge substantially taut.
- Signed at New York in the county of New York and State of New York this 26th day of March, 1930.
- ARTHUR W. MOREE.
